UNITED STATES PATENT OFFICE.

ROBERT M. KENNEDY, OF PITTSBURGH, PENNSYLVANIA.

LIQUID-FUEL BURNER.

Application filed June 22, 1922. Serial No. 570,204.

To all whom it may concern:

Be it known that I, ROBERT M. KENNEDY, a citizen of the United States, and a resident of Pittsburgh, in the county of Allegheny and State of Pennsylvania, have invented a new and useful Improvement in Liquid-Fuel Burners, of which the following is a specification.

This invention relates to burners, and particularly to burners for use in connection with the combustion of liquid fuels.

The object of the invention is to provide a burner adapted for general use which is simple, safe, efficient, easy to operate, which does not require skilled labor and attention, and which effects substantially perfect combustion.

Other objects are to provide a burner in which the air is supplied by natural draft as distinguished from a forced draft, in which the air supply effects a cooling of the fuel supply pipe to the burner, in which the air supply aids in the initial distribution of the fuel to the carbureting vanes which air and fuel are brought into very intimate contact to effect a complete mixture thereof, and in which the combustion is sufficiently perfect to prevent the accumulation of carbon deposits in the apparatus.

These and other objects of the invention will more readily appear when taken in connection with the following description and the appended claims.

In the accompanying drawings which illustrate the preferred embodiment of the invention, Fig. 1 is a vertical transverse sectional view with parts in elevation of the complete burner; Fig. 2, a section taken on the line II-II of Fig. 1; and Fig. 3 a fragmentary sectional view taken on the line III-III of Fig. 2.

As illustrated the burner consists primarily of fuel supply pipe 1, fuel compartment 2, casing 3, deflecting shell 4 and spiral vanes 5.

The diameter of the compartment 2 is considerably greater than that of the fuel supply pipe 1, and is mounted thereon in any suitable manner, as illustrated in Fig. 3, having its top closed by the threaded plug 6, the upper end 7 of which is hexagonal in shape to facilitate the insertion and removal thereof by means of a wrench.

The compartment 2 is embraced by the upper end of the cylindrical casing 3, which depends therefrom, and is spaced from the

pipe 1 to provide an air chamber around the same.

Spaced from and surrounding the casing 3 is the frustro-conical deflecting shell 4 having both ends open for the free passage of air upwardly therethrough. The lowermost edge of shell 4 is provided with a lateral flange 8 to which is attached a supporting bracket 9, suitably fastened to pipe 1 as by bolts 10 and 11, a portion of the pipe being threaded for such purpose.

A plurality of spiral vanes 5 bridge the space between the casing 3 and shell 4, the ends of the vanes terminating at the extremities of the shell, and their upper ends being disposed slightly below the bottom of the compartment 2. The width of the vanes gradually increases from their upper to their lower ends to compensate for the increased distance between the casing and deflecting shell due to the frustro-conical form of the latter. Any number of vanes may be used, three being employed in the embodiment illustrated in the drawings. The upper surfaces of the vanes are provided with a series of marginal baffles 12, arranged in staggered relation, and extending alternately inwards from their opposite edges. These baffles are both thicker and wider at their outer extremities and gradually taper towards their inner ends. Their length is slightly greater than one-half the width of the vanes at the point at which they are located so as to form in effect a serpentine trough throughout the entire extent of the vanes. These baffles may be formed in any desired manner, and in the embodiment shown are made by embossing or upwardly indenting the metal of the vane itself.

Mounted in the bottom of the compartment 2 and extending through the wall of casing 3 is a series of fuel discharge nozzles 13. Each nozzle comprises a downwardly inclined tubular portion 14 open at both ends, and a lateral tube or duct 15 extending through the bottom of compartment 2, and establishing communication between the interior of the compartment and the intermediate portion of tube 14. The number of nozzles employed corresponds to the number of spiral vanes used, the outer end of the tube 14 terminating directly above the upper extremity of its corresponding vane 5 so as to discharge fuel thereon.

The several parts may either be formed

integrally or made of separate parts and suitably connected in any desired manner without affecting the spirit of the invention. It is also noted that although the preferred embodiment of the invention is shown and described without a deflecting top and without means for producing a forced draft, and is preferably used without them, such means may be employed whenever the same are found to be desirable.

In initially starting the burner the same may be heated up in any well known manner, or may be heated by simply igniting the fuel upon the surface of the spiral vanes.

15 The liquid fuel is fed to the pipe 1 under a slight head, and enters the compartment 2 from which it escapes through the duct 15 to the downwardly inclined tubes 14 by which it is conveyed to the upper extremities 20 of vane 5. The fuel deposited on the vanes spreads over the surface thereof in the form of a thin film, and trickles downwardly being deflected from side to side by the baffles 12, causing it to flow in a serpentine 25 path.

An upward draft of air is produced, a portion of the air entering the lower open end of casing 3, and flowing upwardly around the pipe 1, finally escapes through 30 the tube 14, aiding in the discharge of the liquid fuel therefrom. The air blast thus produced through tubes 14 partially atomizes or aerates the liquid fuel and distributes it over the entire width of the vanes 5. The 35 air in rising through the casing 3 serves as a cooling medium and as a heat insulator for the fuel supply pipe 1, the air being gradually heated during its ascent.

Air also passes upwardly between the casing 40 3 and deflecting shell 4, traversing the entire extent of the vanes and flowing in direct intimate contact with the film of fuel trickling downwardly thereon. In this manner an absolute mixing of the air and fuel is obtained, resulting in perfect combustion 45 thereof at the upper end of the burner. By bringing the air into such intimate contact with the fuel and progressively passing it throughout the entire extent of the vanes, the entire quantity of fuel deposited on the vanes is vaporized, deposits of carbon are entirely eliminated, and a perfect combustion 50 free from soot or smoke is secured.

It is thus seen that the invention provides 55 a very simple, compact, economical and efficient burner, and which is free from complications; one in which the fuel supply pipe is maintained cool by a flow of air subsequently used in the operation of the burner; one in which deposits of carbon are eliminated, and one in which perfect combustion 60 is obtained.

I claim:

65 1. A liquid fuel burner comprising a fuel supply pipe having a discharge orifice, an

imperforate inclined vane, the upper end of which is disposed below said orifice to receive fuel discharged therefrom, and means for causing the body of air passing upwardly of said vane to traverse the entire extent of said vane in direct intimate contact with its upper surface.

2. A liquid fuel burner comprising a fuel supply pipe having a discharge orifice adjacent its upper end, a casing surrounding and spaced from the supply pipe, an open ended deflecting shell surrounding and spaced from said casing, an inclined vane positioned between the casing and shell whereby the body of air passing upwardly between the casing and shell traverses the entire extent of the vane in intimate contact with its upper surface, the upper end of the said vane being adapted to receive fuel discharged from said orifice.

3. A liquid fuel burner comprising a fuel supply pipe having a discharge orifice adjacent its upper end, a casing surrounding and spaced from the supply pipe, said casing being open at its bottom and provided with an escape opening adjacent its top, an open ended deflecting shell surrounding and spaced from said casing, an inclined vane positioned between the casing and shell whereby the body of air passing upwardly between the casing and shell traverses the entire extent of the vane in intimate contact with its upper surface, the upper end of the said vane being adapted to receive fuel discharged from the said orifice.

4. A liquid fuel burner comprising a fuel supply pipe, a casing open at its lower end and closed at its upper end surrounding and spaced from the supply pipe, an open ended deflecting shell surrounding and spaced from the casing, an inclined vane bridging the space between the casing and shell, a discharge nozzle for feeding fuel from the supply pipe to the upper end of the vane, and means establishing communication between the interior of the casing and nozzle duct, whereby air within the casing may traverse said duct.

5. A liquid fuel burner comprising a fuel supply pipe, a fuel compartment mounted at its upper end, a casing having an open bottom depending from the compartment and spaced from the supply pipe, a deflecting shell surrounding and spaced from the casing, a spiral vane bridging the space between the casing and shell, a fuel discharge nozzle terminating above the upper end of the vane for feeding fuel thereon from the compartment, the duct of said nozzle having communication with the interior of the casing, whereby the air draft through the casing will aid in discharging fuel therefrom.

6. A liquid fuel burner comprising a fuel supply pipe, a fuel compartment mounted at its upper end, a casing having an open bottom depending from the compartment

and spaced from the supply pipe, a deflecting shell surrounding and spaced from the casing, a spiral vane bridging the space between the casing and shell, the upper surface of said spiral vane being provided with a series of staggered baffles projecting inwardly from its opposite edges to form a serpentine trough, a fuel discharge nozzle terminating above the upper end of the vane for feeding fuel thereon from the compartment, the duct of said nozzle having communication with the interior of the casing, whereby the air draft through the casing will aid in discharging fuel therefrom.

10 7. A liquid fuel burner comprising a fuel supply pipe, a fuel compartment mounted at its upper end, a cylindrical casing having

an open bottom depending from the compartment and spaced from the supply pipe, a deflecting shell surrounding and spaced from the casing, a plurality of spiral vanes disposed between the casing and shell, an inclined open ended tube extending through the casing wall and terminating directly above the upper extremity of each of said vanes, and ducts establishing communication between the fuel compartment and the intermediate portion of each of said tubes.

25 In testimony whereof, I sign my name.

ROBERT M. KENNEDY.
